UNITED STATES PATENT OFFICE.

CHARLES P. NICHOLAS AND JOSIAH M. MYERS, OF DAVENPORT, IOWA.

CHIROPRACTIC APPARATUS.

1,112,646.

Specification of Letters Patent.

Patented Oct. 6, 1914.

Application filed February 13, 1913. Serial No. 748,139.

To all whom it may concern:

Be it known that we, CHARLES P. NICHOLAS and JOSIAH M. MYERS, citizens of the United States, residing at Davenport, in the county of Scott and State of Iowa, have invented new and useful Improvements in Chiropractic Apparatus, of which the following is a specification.

Our present invention pertains to chiropractic tables or apparatus for use by chiropractors; and it has for its general object to provide an apparatus constructed with a view to being compactly folded and carried in a case simulating a suit-case, and also constructed with a view to being expeditiously and easily set up in rigid condition and ready for use.

With the foregoing in mind the invention in all of its details will be fully understood from the following description and claims, when the same are read in connection with the drawings, accompanying and forming part of this specification, in which:

Figure 1 is a side elevation showing the head member of our novel apparatus as set up ready for use. Fig. 2 is a plan, showing the suit-case section member of the apparatus as it appears in inverted position, and when ready to be upset and used in connection with the head member. Fig. 3 is an inverted plan of the head member as it appears when folded. Fig. 4 is a view showing the head member of the apparatus as it appears when properly arranged in folded condition relative to the folded suit-case section member precedent to applying the closure member of the suit-case, so as to make the exterior appearance of the whole simulate an ordinary suit-case. Fig. 5 is a transverse section taken through the apparatus as folded in the suit-case section member and the closure member of the suit-case. Figs. 6, 7 and 8, are enlarged detail views illustrative of the stay-locking device common to the head member and the suit-case section member, as hereinafter described.

Similar numerals of reference designate corresponding parts in all of the views of the drawings.

As will be understood by comparison of Figs. 1, 3 and 4 of the drawings, the head member of our novel apparatus comprises a conventional board 1, tapered in width toward one end, a plate 2 fixed to the underside of said board and designed to hold the head member against longitudinal movement

relative to the suit-case section member when the one is arranged against the other in the suit-case, a transverse strip 3, fixed to the under side of the board 1 and having a groove 4 in its under side throughout its length, a transverse strip 5 of less thickness than the strip 3, also connected to the under side of the board 1, U-shaped straps 6 connected to the strip 3, a tubular metallic journal portion 7 held by the straps 6 in the groove 4 of strip 3, divergent tubular metallic legs 8 fixed to and depending from the journal portion 7, and provided at their lower ends with pads 9, straps 10 connected to the strip 5, a tubular metallic journal portion 11 arranged in said straps, divergent tubular metallic legs 12 fixed to and depending from said journal portion 11 and having pads 13 at their lower ends, a U-shaped stay 14 connected at its ends 15 in a pivotal manner to the legs 8, a similar stay 16 connected in the same manner at 17 to the legs 12, and stay-locking means 18. The said stay-locking means is carried at the under-side of the board 1, and includes a spring strap 19, movable vertically in a groove 20, formed in the underside of the board 1, as best shown in Fig. 8, and equipped with a stud 21. In addition to the said strap 19, the stay-locking device comprises a body plate 22 having lugs 23 and also having a stop 24, Figs. 6 and 8, and an aperture 25, loosely receiving the stud 21, Figs. 6 and 8, and a locking member 26 pivoted to the body plate 22 and adapted in the position shown in Fig. 6 to bring up against the stop 24 and rest over or rather under the pin 21, so as to retain the same flush with or above the underside of the plate 22, and also adapted when in a position at right angles to that shown in Fig. 6, to hold the bights of the stays 14 and 16 in the inner grooved sides of the lugs 23. It will also be manifest that when the locking member 26 is in the position shown in Fig. 1—*i. e.*, in a position at right angles to that shown in Fig. 6, the said locking member 26 will bring up against the stop 24 and stops 27 on the lugs 23, and will be retained against the said stops 24 and 27 by the stud or pin 21, which at that time will have sprung to a position at the opposite side of the locking member 26, with reference to the stop 24. With the stays 14 locked as described, it will be manifest that there is no liability of the said stays being casually released, and hence the stays will rigidly

and safely hold the legs 8 and 12 in the working position shown in Fig. 1.

When it is desired to fold the head member, the strap 19 is pressed into the board 1 by pressure exerted on its thumb-piece 28, and so as to withdraw the stud 21 from the underside of the body plate 22, after which the centrally pivoted locking member 26 is adjusted or moved to the position shown in Fig. 6 and against the stop 24. With this done, the stays 14 can be readily displaced from the lugs 23, after which the legs 12 are swung to a position close and parallel to the underside of the board 1, the bight portion 15 of the stay 16 being carried through a recess 29 in the strip 3. With the legs 12 and stays 16 folded and accommodated as stated, the legs 8 are folded against the legs 12, and the stay 14, or rather the bight portion of said 20 stay, is extended through a recess 30 provided in the strip 5. As thus folded, the head member is adapted to be placed in proper relation to the suit-case section member, and the suit-case closure section, so that 25 the same can be carried with the same convenience as an ordinary suit-case. See in this connection Figs. 4 and 5.

As will be observed by reference to Figs. 1, 4 and 5, the suit-case-section member of 30 our apparatus comprises a body similar to the larger section of a suit-case. The said body has a main wall 31 and side walls 32, one of which bears a handle 33, and when 35 said body is supported by the legs under the same, and is arranged in proper relation to the head member of Fig. 1, the whole constitutes an efficient and convenient chiropractic apparatus.

In addition to the body referred to, the 40 suit-case section member comprises blocks 34 connected to the inner side of the body wall 31, a strip 35 shallower than the blocks 34 also connected to said wall 31, journal-bearing straps 36 and 37 connected to the 45 blocks 34 and strip 35, respectively, a tubular metallic journal portion 38 disposed in the straps 36, tubular metallic legs 39 fixed to the journal portion 38, a bail-shaped stay 40 pivoted to the legs 39, a tubular metallic 50 journal portion 41 disposed in the straps 37, tubular metallic legs 42 fixed to the journal portion 41; the said legs 39 and 42 being provided with pads 43. Fig. 4, a bail-shaped stay 44 pivoted to the legs 42, and a locking 55 device 18 similar in construction to the locking device of the head member and adapted to coöperate with the stays 40 and 44 in the same manner and for the same purpose that the said locking device of the head member, 60 Fig. 1, coöperates with the stays 14 and 16, Fig. 1.

With the parts arranged as shown in Fig. 2, it is simply necessary to upset the suit-case section member and stand the body 65 thereof on its legs in order to adapt said

member for chiropractic use in conjunction with the head member of Fig. 1. When it is desired to fold the said suit-case section member, the stays 40 and 44 are unlocked, and said stays together with the legs 42 and 39 are swung inwardly and parallel to the body wall 31; the legs 42 being next to said wall. In addition to the head member of Fig. 1, and the suit-case-section member of Fig. 2, our novel apparatus comprises a 75 suit-case-closure member 50, Fig. 5.

In folding the apparatus, the head member, folded as shown in Fig. 3, is arranged with its legs against the legs of the folded suit-case-section member as shown in Fig. 80 4; the plate 2 of the head member bearing against one of the tubular metallic journal portions of the suit-case-section member, so as to prevent endwise play of the head member relative to the suit-case-section member. 85

When the head member and the suit-case-section member are relatively arranged as shown in Fig. 4, and the suit-case-closure member 50 is applied and connected to the suit-case-section member, as presently described, it will be manifest that the head member will be crowded against the interior parts of the suit-case-section member, whereupon by reason of the resiliency or springiness of the tubular metallic legs and said legs 90 being put under tension, shaking of the parts in the case will be effectually prevented and movement of the head member relative to the suit-case-section member will be effectually prevented, which is an important advantage. 100

The suit-case-closure member 50 is preferably, though not necessarily, connected in detachable manner to the body of the suit-case-section member. In the present and 105 preferred embodiment, the member 50 is provided with projecting tongues 51 on its lower wall, removably arranged in sockets 52 in the lower wall of the body of the suit-case-section, and the upper wall of the member 110 50 is detachably connected with the upper wall of the body of the suit-case-section member by the conventional fastener members 53 common in the trunk and suit-case art, or by any other suitable means. 115

Manifestly when the parts are relatively arranged as shown in Fig. 5, and the suit-case members are connected together, the apparatus can be handled and carried with the same convenience as an ordinary suit-case. Also when it is desired to set up the apparatus, it is simply necessary to unfasten the member 50, remove and unfold the head member, and unfold the suit-case-section member, when the said head member and the suit-case-section member can be used in the same manner and for the same purposes as the corresponding members of an ordinary chiropractic apparatus. It will also be manifest from the foregoing that certain 120 125 130

features of my invention may be used to advantage in a table of any description.

We have entered into a detailed description of the construction and relative arrangement of the parts comprised in the present and preferred embodiment of our invention, in order to impart a full, clear and exact understanding of the said embodiment. We do not desire, however, to be understood as confining ourselves to the said specific construction and relative arrangement of parts as, in the future practice of the invention, such changes or modifications may be made as do not involve departure from the scope of our invention as claimed. For instance the locking device described may be used on a table of any description.

Having described our invention, what we claim and desire to secure by Letters-Patent, is:

1. The combination with a table having a top and legs hinged thereto; of a base plate fixed to said top and having an aperture and also having depending lugs constructed and arranged to receive brace means and also having a stop, the said brace means engaging said legs and fitting said lugs, a turn-button pivotally mounted upon said plate and constructed and arranged to bring up against said stop and to hold said brace means against said lugs, a spring secured at one end to the top and movable between said top and said base plate, and a pin on said spring, extending through the aperture in the base plate to hold the turn-button against said stop.

2. The combination of a member, strips connected to the under side of said member near the ends thereof; one of said strips being deeper than the other, and the strips being constructed and arranged to serve in conjunction with the under side of the member to form horizontal recesses, transverse journal portions mounted on the under sides of the strips and arranged below said hori-

zontal recesses, legs fixed to said journal portions, bail-shaped stays pivoted to the legs and constructed and arranged in their folded positions to extend through said horizontal recesses, whereby their free portions 50 are retained against the under side of the member, and means on the member constructed and arranged to coöperate with the stays and detachably secure the stays and the legs in their operative positions. 55

3. The combination with a table having a top and legs hinged thereto, of a base plate secured to said top provided with lugs extending vertically therefrom and provided with thickened body portions, said lugs provided with longitudinally extending notches near their inner portions, brace means engaging said legs and fitting within said notches for holding the legs in an extended position, a turn-button pivotally mounted 60 upon said plate and provided with a rectangular body portion, the edges of said body portion fitting between said lugs at a spaced distance therefrom for holding said brace means in engagement with said lugs, 65 means carried by said lugs for limiting the rotation of said button in one direction, said base plate provided with an aperture, a spring secured at one end to said top at a distance from said plate, a pin carried by 70 the free end of said spring, said pin adapted to fit in said aperture for holding said turn-button in engagement with said means on the lugs, the upper portion of said lugs being beveled for facilitating the introducing 75 of said brace means behind said lugs and into engagement with said notches.

In testimony whereof we have hereunto set our hands in presence of two subscribing witnesses.

CHARLES P. NICHOLAS.
JOSIAH M. MYERS.
